UNITED STATES PATENT OFFICE.

FRANK B. COMINS, OF NEWTON, AND JOSEPH ARMSTRONG, OF MALDEN, MASSACHUSETTS, ASSIGNORS TO AMERICAN MOISTENING COMPANY, OF BOSTON, MASSACHUSETTS, A CORPORATION OF MAINE.

HUMIDIFIER.

Original application filed July 14, 1921, Serial No. 484,633. Divided and this application filed March 1, 1924. Serial No. 696,332.

This invention relates to an improved humidifier. More especially it relates to improved means constituting both a support for a humidifier and a conduit for water that passes through the motor thereof. The 5 invention in its broader aspects is disclosed and claimed in our co-pending application, which has become Patent No. 1,504,431 of August 12, 1924, entitled Humidifiers, of 10 which this is a division.

In humidifiers embodying a water motor for driving a fan, the humidifier as a whole, including the casing, water motor, fan and spray nozzle, are usually suspended from 15 some overhead support by hangers or the like. In addition the water used as motive force has been conducted to the motor through supply pipes, and away from it through discharge pipes. The present invention provides for the elimination of some 20 of these parts, in that it combines them into tubular members which serve both as conduits for the water and as supports for the apparatus; and this particular division 25 thereof provides conduit hangers having connections with a water motor which discharges its used water through them into the base or pan without separate drainage piping being required.

It is a feature of the invention that this 30 discharge is conducted through the conduit hangers into the pan of the humidifier casing, and thence flows off through the ordinary drain pipe.

Accordingly the hangers are made with 35 tubular sections to which the casing is attached, or which may in fact be part of the casing, and into which suitable connections lead from the discharge exits of the 40 water motor. At the lower ends of the tubular sections, just before their junction with the pan, openings are provided in the sections from which the water may discharge into the pan. The flow of this water 45 helps flush the pan and carry off foreign matter through the regular drainage system thereof.

In the accompanying drawing, the invention 50 is shown in its particular application to a motor having a two-way discharge, but this is merely illustrative of the principle of the invention. The patent is intended to

cover, by suitable expression in the appended claims, whatever features of patentable novelty exist in the invention disclosed, 55 and not heretofore claimed in our co-pending application hereinbefore mentioned.

In the drawings:

Figure 1 is a front elevation, showing a 60 humidifier embodying the present improvement;

Figure 2 is a side elevation of the same, looking from the right of Figure 1; and

Figure 3 is an enlarged elevation showing 65 the details of the lower end of one of the conduit hangers.

Referring to the drawings, a nozzle 10, within the humidifier casing 11 provides a conical spray above which a water motor 12 is supported carrying on its shaft a fan 13 which forces air through the casing and through the conical spray. The casing as a 70 whole is supported by a pair of hanger members each having a tubular portion 14 whose upper end screws into a socket 15 attached to the ceiling, and whose lower end engages a perforated nut 16 having a stem 18 which projects downward through the bottom of the pan 19 to receive a clamping nut 20 for holding the pan. The outlets 75 from the motor are connected direct to the tubular portions 14 through two-part tubular connections 21 each having a union 31 in its midst, between its two parts.

Water may be supplied to the motor 80 through a branch 22 of the main supply system 23 for the nozzle, there being a control valve 24 and filter 25 in the system ahead of the branch and a diaphragm control valve 26 between it and the nozzle, by 85 which the performance of the humidifier can be automatically controlled by any well known means of humidity regulating apparatus. The water having done its work in driving the motor passes through the connections 21 into the tubular portions 14 of the conduit hangers, and thence through them to the nuts 16 where it flows out 90 through the holes 27 to the pan. It then drains from the latter into the waste pipe 95 28, assisting by its volume and force in removing any lint or foreign particles that may be deposited on the pan.

The tubular hangers thus serve both as

supporting members for the humidifiers and as conduits for the motor discharge, thereby reducing the parts heretofore provided, with economy of construction and with 5 greatly improved appearance of the entire apparatus.

We claim:

1. In a humidifier the combination, with a water motor, of a tubular hanger 10 adapted to support the humidifier, connected with the motor for receiving its dis-

charge and itself having a discharge opening into the humidifier base.

2. A humidifier having a casing, a spraying nozzle therein, a pan thereunder with 15 discharge outlet, a fan and a water motor therefor; combined with a pair of pipes adapted to support the humidifier; said pipes also constituting a motor-water passage discharging into the pan.

FRANK B. COMINS.
JOSEPH ARMSTRONG.
